DESIGN FOR A VIAL HOUSING UNIT

Adolph Langsner, Chicago, Ill., assignor to Eugene Dietzgen Company, Chicago, Ill., a corporation of Delaware

Application August 25, 1934, Serial No. 53,062

Term of patent 14 years

To all whom it may concern:

Be it known that I, Adolph Langsner, a citizen of the United States, residing at Chicago, Cook County, Illinois, have invented a new, original, and ornamental Design for a Vial Housing Unit, of which the following is a specification, reference being had to the accompanying drawing, forming part thereof,

Figure 1 is a side view of a vial housing unit showing my new design; and

Figures 2 and 3 are, respectively, top and bottom fragmentary views of the vial housing unit.

I claim:

The ornamental design for a vial housing unit as shown,

ADOLPH LANGSNER,
